AIR SUPPLY CONTROLLING MEANS

Filed Dec. 7, 1929

UNITED STATES PATENT OFFICE

WILLIAM H. KITTO, OF CANTON, AND ROY G. ROSHONG, OF NORTH CANTON, OHIO,
ASSIGNORS TO THE HOOVER COMPANY, A CORPORATION OF OHIO

AIR SUPPLY CONTROLLING MEANS

Application filed December 7, 1929. Serial No. 412,416.

This invention relates to sprayers and similar devices, and more particularly to means for controlling the operation of a sprayer or other device which is supplied with a continuous current of air. One of the objects of the invention is to provide a sprayer which is of rugged and simple construction and which can be economically manufactured. A further object is to provide a device of the type which can be conveniently used, and in which the spraying action can be easily and effectively controlled between wide limits and any tendency to "dribble" will be avoided. A still further object is the provision of simple and efficient means for controlling the flow of air from a source of continuous supply to a device of this kind by which the air flow can be varied as desired without materially varying the back pressure upon the air supplying means. Still further objects of the invention, as well as the novel features of construction and operation, will be understood upon a reading of the following description of various embodiments of the invention shown in the accompanying drawing, in which:

Fig. 1 is a plan view of a sprayer embodying the invention;
Fig. 2 is a view in longitudinal section, partly in side elevation, of the structure shown in Fig. 1;

Fig. 3 is a fragmentary central longitudinal sectional view, of the structure shown in Figs. 1 and 2, but showing a slightly modified detail;

Figs. 4, 5, 6 and 7 are fragmentary views in longitudinal section showing modified details of construction;

Fig. 8 is a fragmentary transverse sectional view of the structure shown in Fig. 7 and taken on line 8-8 of Fig. 7; and

Fig. 9 is a fragmentary transverse sectional view of a still further modification.

As shown in Figs. 1 and 2, the main body of the device is in the form of a cover portion or top 11, having interrupted threads 12, and adapted to have detachably secured thereto a container 13, such as a jar of glass or similar material, which is provided

with cooperating threads. A horizontal blast tube portion 14 extends upwardly from the top 11, being provided with a bore 15, and extending diametrically of the top beyond one edge thereof, where it joins a downwardly and laterally extending tubular handle portion 16. The cover or top 11, the blast tube 14 and the tubular handle 16 may be conveniently formed as a casting of aluminum or an aluminum alloy. Since the device shown in the drawing is intended for use with a vacuum cleaner the handle 16 is preferably of a diameter suitable for convenient attachment to the hose commonly used for the attachment of dusting tools to such a cleaner, while the bore 15 of the blast tube is of much smaller diameter.

A liquid tube 17 is carried by the cover 11, being threaded into a hollow reinforcing member 18 which extends through the cover 11 and is riveted against the upper face of the cover as shown at 18a. The lower end 19 of the liquid tube preferably extends at a slight angle to the body of the tube so as to reach well into the corner formed between the bottom and the wall of the container and provide for the atomization of practically all of the liquid content, and the tube 17 is held in its vertically adjusted position, and held from rotation by a nut 20 threaded upon its upper end and engaging the top of the cover 11. The blast tube 14 is formed with an annular shoulder 21, for a purpose which will be later described, and at that end adjacent the liquid tube 17 it receives a nozzle 22 which is frictionally mounted therein so as to be longitudinally and rotatably adjustable, the tube being machined to form a counterbore 23, if desired, to provide for accurate fitting of the nozzle. An opening 24 extends through the nozzle 22 in line with the upper end of the liquid tube 11, and the nozzle is preferably formed with diverging arms having bores 25 therein connecting with converging bores 26 to direct jets of air which will meet in line with the jet from the opening 24 but beyond the upper end of the liquid tube.

An opening 27 is provided to permit air to pass from the blast tube 15 through the

cover 11 to maintain a pressure on the surface of the liquid equivalent to that in the blast tube.

As shown in Fig. 1, a vent opening 28 is provided in the cover 11, with a plate 30, pivoted at 31, and turned up at 32 to facilitate manipulation, and having an opening 29 therein by which the opening may be covered to any extent desired. It will be apparent that by varying the effective size of the opening 28 one may vary the pressure maintained above the surface of the liquid during operation and thus vary the rate of flow of the liquid.

15 In the operation of sprayers of this type it is desirable to avoid materially increasing the back pressure upon the air-supplying device, and valves which prevent the flow of air are objectionable not only for such reason but also because of the danger of sticking and the cost of their manufacture. In the structure shown herewith the flow of air through the blast tube 14 is controlled by arranging the tubular handle 16, through 25 which the air is supplied, substantially at right angles to the blast tube and forming an opening 33 in direct line with the direction of flow in the handle portion and of such size as to afford no material restriction to the flow. The opening 33 preferably narrows toward its forward end and both ends are rounded, the construction of the casting being preferably such that the entire upper edge about the opening will lie in a plane 35 almost perpendicular to the handle 16.

A baffle 34 is positioned to extend rearwardly from the blast tube 14 into the tubular handle 16 and preferably presents a convex surface to the flow of air. As shown 40 in Figs. 1 and 2, the baffle 34 is spoon-shaped and may be conveniently formed as a stamping having lateral portions 35 bent up to form a split ring which fits frictionally within the bore 15 and is slidable longitudinally 45 therein, its rearward movement being limited by the shoulder 21 heretofore described. The baffle may likewise take the form shown at 36 in Figs. 3, 4, 6, 7, 8 and 9, and be secured in place by a rivet 37, or other suitable 50 means.

In order that the flow of air through the relatively larger opening 33 may be efficiently and conveniently controlled by the thumb of the hand in which the sprayer is supported, a flap valve is yieldably supported for movement toward said opening. As shown 55 in Figs. 1 and 2, the flap valve is formed from a tube of rubber, or similar material, with a circular base portion 38 adapted to 60 encircle and be frictionally held in position upon the tubular handle 16, and an integral tapering upper flap portion 39 which is normally positioned in extension of the handle 16, but can be readily bent 65 down by the thumb to gradually close the

opening 33, the material bulging out slightly from the handle adjacent the line of bend. In the construction shown in Fig. 4, the plane of the opening 33a forms a sharper angle with the handle 16, and the upper edge of the base portion 38a meets the parallel sides of the flap portion 39a substantially at right angles, so that the length of the line of bend is only slightly greater than the width of the opening 33a. As shown in Fig. 5, the flap portion 39b may be stiffened, if desired, by a metal or other rigid plate 40 molded or otherwise secured therein.

In the construction shown in Fig. 6, the base portion 38c is split and surrounds the blast tube 14, being held in place by a spring clamp 41, and the stiffening plate 40c is formed with holes, the material at the edge of such holes being bent, to hold the plate from being displaced. In Figs. 7 and 8 the opening 33d is in line with the upper edge of the blast tube 14, and the rubber flap 39d is formed with an annular lip 42 adapted to fit within the opening, the flap being mounted on a tongue 43 of spring metal having lateral portions 44 bent down to form a clamp which will snap upon the blast tube 14. The flap may also be hinged to the side wall of the handle 16 adjacent its upper end as shown in Fig. 9, by riveting or otherwise securing a supporting member 45 to the handle 16 and pivotally securing to it a metal plate 46 which carries the flap 39e, a spring 47 being mounted on the hinge pin and engaging the parts to hold the flap normally in elevated position above the opening 33e.

When the flap valve is open the flow of air upward through the tubular handle 16 meets practically no resistance, and there is no flow through the blast tube and hence no tendency for the liquid to dribble from the tube 17 even through the sprayer is tilted forward until the liquid level reaches the top of the tube. The baffle 34 or 36 causes a slight eddy which further assists in preventing flow through the blast tube. As the flap is moved toward the opening 33 it also approaches the upper edge of the baffle and in the modifications shown in Figs. 1, 2, 3 and 4 can be bulged inwardly toward the lip of the baffle. The spacing between the upper edge of the baffle and the inner surface of the flap will be greater at the sides than at the lip, the area of the opening as a whole being less than that of the tubular handle 16, so that an eddy will be produced within the blast tube and can be altered by movement of the valve flap.

The opening 27 permits a pressure to be maintained upon the surface of the liquid which is substantially equal to that at the nozzle opening 24, if the vent opening 28 is closed, and by varying the effective size of such vent opening the relative pressure

upon the surface may be reduced to lower the rate at which the liquid will be atomized.

While various embodiments of the invention in a spraying device have been shown and described, it will be understood that the invention may be applied to any device in which it is desired to control the flow of air from a continuous supply to effect intermittent flow, and that many changes in details of construction may be made within the scope of the invention as defined by the following claims.

We claim:

1. An air-supply tube having angularly disposed portions one of which is adapted to act as a handle, there being an opening in the wall of said tube where said portions join, and means for controlling the flow through said tube comprising a tubular member of resilient material fitting upon one portion of said tube and having an integral flap portion overlying said opening.

2. An air-supply tube having an opening in its wall and a rubber ring fitting upon and frictionally engaging said tube, said ring having a flap portion integral therewith overlying and normally spaced from said opening.

3. A sprayer device comprising an air supply tube having angularly disposed portions one of which is adapted to act as a handle, said tube having a baffle therein adjacent the juncture of said portions and having an opening in its wall adjacent said baffle, said baffle being positioned to divert air through said opening, and a flap member resiliently supported upon the outside of said tube and overlying said opening.

4. An air supply tube comprising connecting angularly disposed portions, there being an opening in the wall of said tube in line with the bore of that portion through which the air first passes, a baffle disposed normally to prevent entry of air into the other of said portions, and means for varying the flow of air into the other of said portions comprising a flap resiliently held away from but movable toward said opening.

5. A sprayer comprising an air supply tube having angularly disposed portions one of which is adapted to act as a handle, said tube having an opening in its wall and a baffle within the tube adjacent such opening and normally directing air flow through said opening, a liquid container underlying a portion of said tube, a tube extending upward from said container into the path of flow through said air supply tube, the upper portion of said container being continuously in communication with said air supply tube and having a vent to atmosphere.

6. A sprayer device comprising an air supply tube having an abrupt bend therein, there being an opening in the wall of said tube adjacent said bend, in line with and of

substantially the same area as the cross section of one portion of said tube, and a valve member for controlling the flow through said opening comprising a flap and means for supporting said flap on the outside of said tube.

7. A sprayer device comprising an air supply tube having angularly disposed portions one of which is adapted to act as a handle, said tube having an opening in its wall at the outside of the bend in said tube adjacent the juncture of said portions, and a cup-shaped baffle in said tube adjacent said opening having its convex surface projecting laterally into the air stream in line with the handle portion of said tube to direct air through said opening.

8. An air supply tube, said tube being bent and having an opening in its wall at the outside of the bend of said tube, and means for controlling the flow of air through said tube comprising a flap positioned adjacent said opening and having a portion thereof frictionally and resiliently engaging the outside of said tube and constituting the sole support for resiliently supporting said flap for movement toward said opening.

9. A sprayer device comprising an air supply tube having angularly disposed portions one of which is adapted to act as a handle, said tube having an opening in its wall adjacent the juncture of said portions in line with the handle portion, and a baffle mounted in the other portion of said tube adjacent said opening and having a part thereof projecting into the handle portion in line with and spaced from the plane of said opening.

Signed at North Canton, in the county of Stark, and State of Ohio, this 2nd day of December, A. D. 1929.
